UNITED STATES PATENT OFFICE

148,454

DESIGN FOR A CERAMIC TABLE TILE

Herbert G. Blakeslee, Evanston, Ill., assignor to Cory Corporation, Chicago, Ill., a corporation of Delaware

Application July 15, 1946, Serial No. 131,575

Term of patent 14 years

(Cl. D44—10)

To all whom it may concern:

Be it known that I, Herbert G. Blakeslee, a citizen of the United States, residing at Evanston, in the county of Cook and State of Illinois, have invented a new, original and ornamental Design for a Ceramic Table Tile, of which the following is a specification, reference being had to the accompanying drawing, forming a part thereof, wherein:

Figure 1 is a top plan view of a ceramic table tile showing my new design; and

Fig. 2 is a side elevation thereof.

I claim:

The ornamental design for a ceramic table tile, as shown.
